UNITED STATES PATENT OFFICE.

LESTER KIRSCHBRAUN, OF EVANSTON, ILLINOIS, ASSIGNOR TO FLINTKOTE COMPANY, OF BOSTON, MASSACHUSETTS, A CORPORATION OF MASSACHUSETTS.

ROOFING ELEMENT.

Application filed December 31, 1920. Serial No. 434,389.

To all whom it may concern:

Be it known that I, LESTER KIRSCHBRAUN, a citizen of the United States, residing in the city of Evanston, county of Cook, and 5 State of Illinois, have invented certain new and useful Improvements in Roofing Elements, of which the following is a specification.

This invention relates to improvements in 10 roofing elements and process of making same, and is more particularly adapted to that type of roofing element commercially known as cross-cut shingle strips, such as are shown in patent to F. C. Overbury, No. 15 1,150,298. The essence of the present invention consists in making a shingle strip which will simulate a plurality of shingles but which, instead of being notched as in said Overbury patent, is slotted along that portion 20 of the strip corresponding to the notched portions of said Overbury patent, the slots, however, terminating in closed ends at the edge of the strip instead of having notches open at one end. By doing this, 25 a reinforcement is obtained along the entire edge of the strip so as to produce a strip having uninterrupted edges. This will also tend to prevent curling of the shingles after laid on the roof.

30 In the drawings, Fig. 1 is a top plan view of the completed product. Fig. 2 is a sectional view taken at lines 2—2 of Fig. 1.

Referring to the drawings, 1 designates the foundation or backing of the strip, 35 which may consist of ordinary asphalt saturated felt. This is provided with usual coating 2, to which is adhesively secured the granular facing 3. This granular facing is applied over the entire face of the roofing 40 length in the same way as roll roofing is made, and the roofing sheet may then be slotted as shown at 4, these slots terminating short of the front edge of the strip. Each slotting knife, which may be mounted 45 on a rotating cutter, may be also provided with a boss portion to force the granular

facing down at the extreme edge of the sheet and directly in front of the slot as shown at 5. The sheet may be severed transversely along the line 6 to form the shingle strip. 50 Instead of forcing the granular facing down by means of a boss at the points 5, these points may be painted, as for example with black paint, the result being that when the shingle strips are laid in the usual overlapping manner on the roof, they will give the appearance of separated shingles, the black portion 5 blending into the slotted portions and simulating a completely cut edge. 55

I claim as my invention:

1. A shingle strip having a felted fibrous base coated with an adhesive material, a granular surfacing applied thereto, slots extending transversely across said strip near one end, and terminating short of that end 65 to present an unbroken closed lower edge when the shingle is laid, the connecting unbroken portions thus provided being of a different color than the major color of the strip. 70

2. A shingle strip having a felted fibrous base coated with an adhesive material, a granular surfacing applied thereto, slots extending transversely across said strip near one end, and terminating short of that end 75 to present an unbroken closed lower edge when the shingle is laid, the closed portions adjacent the slots having the granular surfacing pressed into the adhesive material.

3. A shingle strip having a felted fibrous 80 base coated with an adhesive material, a granular surfacing applied thereto, spaced interior slots extending transversely across said strip near one end, and terminating short of that end to present an unbroken 85 closed lower edge when the shingle is laid, the connecting unbroken portions thus provided between the slots having the granular surfacing pressed into the adhesive material, these webs exhibiting a darker color. 90 than the color of the sheet.

LESTER KIRSCHBRAUN.
